UNITED STATES PATENT OFFICE

2,599,108

SHUTTLE BOX

Harold Hoeber, deceased, late of Dartmouth, Mass., by Barbara O. W. Hoeber and William T. Read, executors, Dartmouth, Mass., assigns, by mesne assignments, to Hoosac Mills Corporation, Boston, Mass., a corporation of Massachusetts

Application January 28, 1947, Serial No. 724,726

9 Claims. (Cl. 139—187)

1

The present invention relates generally to shuttle boxes for looms and, as illustrated herein, relates more particularly to mechanism for controlling the pressure of the binders in such shuttle boxes.

In modern high speed looms, picking of the shuttle begins before the lay reaches the midportion of its rearward movement and the shuttle enters the shuttle box on the other side of the loom after the lay has reached back center and has begun its forward movement and the shuttle is usually completely boxed shortly before the lay has reached the forward limit of its forward movement. The shuttle box in which the shuttle is boxed includes a front box plate and a back binder which is pivotally supported at its outer end. The binder is provided with a swell which is engaged by the incoming shuttle and which causes the binder to rock rearwardly against the pressure of a binder spring and against the pressure of the protector rod spring. The pressure of the binder spring and the protector rod spring does not vary appreciably, and as a result, the shuttle must enter a relatively tight box since substantial pressure must be maintained on the protector rod to insure that the dagger on the protector rod will be maintained in protecting position until the shuttle has entered the shuttle box a distance sufficient to operate the protector mechanism. Increase in loom speed necessarily requires increased protector rod spring pressure. Thus, in order to obtain adequate protection, substantial increased pressure is applied to the binder as the speed of loom increases. This pressure causes difficulties in operation since a large amount of power is necessary to pick the shuttle out of the shuttle box and to drive it completely home into the shuttle box on the other side of the loom.

A reduction in pressure applied to the binder at the time that the shuttle is checked results in a substantial reduction in the power required to pick the shuttles across the loom. If less power is required, then there will be a reduction in speed of the shuttle as it enters the opposite shuttle box. A reduction in binder pressure both when the shuttle is being picked and when it is being checked, results in less wear on the shuttle and on the entire picking mechanism including the lug straps and the check straps.

One object of the present invention is to provide an improved construction whereby a wide variation in binder pressure may be obtained while still maintaining adequate pressure necessary to obtain protection. To this end and in accordance with one feature of the invention, means

2

has been secured to the loom frame in position to be engaged by the protector mechanism as the lay approaches top center and which increases the pressure thereon until back center is reached, 5 on forward movement of the lay the pressure is decreased in the reverse order and is at a minimum when the dagger reaches the normal position of the frog steel at a location to engage the same in the absence of a properly positioned 10 shuttle in a shuttle box. As illustrated, the means includes an arm pivoted to the loom frame and which is rocked rearwardly by the lay against the pressure of a coiled or spiral spring. The tension of the spring is easily and conveniently adjusted 15 and the position of the pivoted arm may be easily varied to change the point at which the lay is engaged thereby.

Another object of the present invention is to improve generally upon the construction and operation of looms.

With the above and other objects and features in view, the invention will now be described with particular reference to the accompanying drawings which illustrate a preferred embodiment of 25 the invention and in which:

Fig. 1 is a plan view of a portion of a loom in which the present invention is embodied showing the lay at back center;

Fig. 2 is a similar view showing the lay at front center;

Fig. 3 is a view, partly in section taken along the line III—III of Fig. 1; and

Fig. 4 is a view in section taken along line IV—IV of Fig. 1.

Only a portion of a loom has been shown in the accompanying drawings since the loom generally is of conventional construction and detailed description of the parts not shown is not necessary for an understanding of the present invention.

A left hand shuttle box 10 is mounted on a usual lay 12 which is reciprocated forwardly and rearwardly by usual mechanism (not shown). The shuttle box 10 includes a usual front box plate 14 and a back binder 16 pivoted at 18 to the lay end 20. The back binder 16 is normally urged inwardly of the shuttle box by a leaf spring 22 fixed to the lay end in the usual manner by machine screws 24. The binder 16 is provided with a friction surface 26 formed preferably of leather. Adjacent its inner end, the binder 16 is provided with a swell 28 which is engaged by an incoming shuttle 30 and causes the binder to rock rearwardly about the pivot 18 against the pressure of the spring 22.

An adjustable contact member 32 fixed to the

upper end portion of a dagger finger 34 also engages the binder 16. The dagger finger 34 is connected to a protector rod 36 which is normally urged in a clockwise direction, as viewed in Fig. 3, by a usual torsion spring 38. Thus, when the binder 16 is rocked rearwardly, it must move also against the tension of the spring 38. If the shuttle 30 fails to enter the shuttle box a distance sufficient to rock the protector rod 36 to lift the dagger 40 above a frog steel 42, the loom will be stopped by the usual stop mechanism before damage to the loom or to the warp can occur. The stop mechanism includes the usual frog 44 in which the frog steel 42 is mounted. The frog steel 42 and the end of the dagger 40 are so positioned to each other that the dagger 40 will contact the frog steel 42 shortly after the lay 12 reaches bottom center. If a shuttle has operated the protection mechanism before the lay has reached this position, the dagger 40 will be raised and will not contact the frog steel 42.

The parts so far described are of usual construction and need not be further described in detail since the construction and operation of these parts are well known to those skilled in the art.

In the present embodiment of the invention, the tension of the torsion spring 38 is reduced until it is just sufficient to support the protector parts in protecting position. Thus only very light pressure is transmitted to the binder 16 by the dagger finger 34. The pressure of the binder spring 22 may be dispensed with entirely, if so desired, but at most it is only sufficient to hold the binder 16 in position when the protector mechanism is operated by a shuttle in the opposite shuttlebox. It is desirable to supplement the light spring pressure on the protector rod 36 as provided by the spring 38 at the time of the reversal of movement of the lay at back center so as to overcome the inertia of the dagger finger 34 and assure that it is moved to protecting position in the absence of a properly positioned shuttle in the shuttle box. Accordingly, as the lay moves rearwardly, the dagger finger 34 engages an arm 58 which applies additional pressure on the protecting mechanism. The dagger 34 engages this arm 58 as the forward end 40 of the dagger reaches approximately the rearward end of the frog steel 42, and the pressure increases as the lay moves rearwardly, as more fully explained in the following.

A supplementary spring mechanism is provided to engage the dagger finger 34 during the period when protection is essential to prevent damage to the loom or to the warp thereon. This mechanism includes a plate 46 fixed to a side frame 48 of the loom by a bolt 50 passing through an elongated slot 52 which permits forward and rearward adjustment of the plate 46 relatively to the side frame 48. A vertical stud 54 is fixed to the forward position of the plate 46 by a nut 56. A rocker arm 58 is pivoted to the stud 54 and is maintained in position by a nut 66 which is threaded to the upper end thereof. The arm 58 is urged in a counter-clockwise direction, as viewed in Figs. 1 and 2, by a torsion spring 60 which is secured at one end portion 64 to vertical stud 54 and which has its other end 62 bearing against the rocker arm 58. The plate 46 is provided with an upstanding plate of projection 70 through which a stop screw 72 is threaded to engage the extension or arm 74 of the rocker arm 58 to limit movement thereof under the influence

of the spring 62. The stop screw 72 is locked in adjusted position by a lock nut 76.

The arm 58 is preferably so positioned that it is engaged by the dagger finger 34 as the lay 10 reaches substantially the midpoint of its rearward movement or top center. This adjustment is provided initially by the slot 52 in the plate 46 and fine adjustment is provided by the stop screw 72 which is adjusted so that the arm will engage the dagger finger 34 at the desired point in the rearward movement of the lay 12. The position of the end of the dagger finger 40 and the frog steel 42 is such that when contact is made between the arm 58 and the finger 34, the end of the finger 40 just overlies the rear end of the frog steel 42. The pressure of the arm 58 against the dagger finger 34 is very light at the beginning of contact but reaches a maximum when the lay is at the rearward limit of its movement or at back center and the pressure of the arm 58 decreases as the lay moves forwardly until the arm 74 engages the stop 72. The pressure continues until the dagger 40 reaches the frog steel 42. Pressure of arm 58, although it decreases, is sufficient in conjunction with spring 38 to hold the dagger finger 40 in its lowered protecting position in the absence of the shuttle. In Fig. 1, the parts are shown with the lay 12 at back center and the maximum pressure applied to the dagger finger 34.

When the lay 12 moves rearwardly, the shuttle 30 is picked out or almost out of the shuttle box before the arm 58 engages the dagger finger 34, and this engagement takes place at approximately top center. The shuttle continues its flight and enters the opposite shuttle box before the lay reaches bottom center or the midpoint of its forward movement. At this point, the pressure of the arm 58 on the dagger finger 34 is nearly at its minimum, and the shuttle thus enters relatively freely into the box. The shuttle at that point, as it enters the box, operates the protection mechanism before the forward end of the dagger finger 40 engages the frog steel 42. Thus, the dagger is maintained in protecting position not only by the protector rod spring but also by the pressure of the spring 60 bearing against the rocker arm 58, and pressure of the rocker arm 58 is maintained against the dagger finger 34 until the shuttle has entered the box sufficiently to operate the protector mechanism. The shuttle is completely boxed before the lay reaches front center. As a matter of fact, the shuttle is brought to rest against the picker when the lay is approximately one inch from front center.

In the present loom, the shuttle is picked out of the shuttle box before the lay reaches top center and before the arm 58 engages the dagger finger 34. In the present construction, the timing is such that the arm 58 engages the dagger finger 34 just before the shuttle has broken contact with the binder. Thus, when additional pressure is applied to the binder by the arm 58, it will have no effect on the picking of the shuttle since the movement of the shuttle out of the shuttle box is much more rapid than movement of the binder inwardly of the shuttle box. The pressure of the arm 58 on the dagger finger 34, as above stated, approaches its maximum as the lay approaches back center.

Having thus described the invention, what is claimed as new and desired to secure by Letters Patent of the United States is:

1. In a loom, a loom frame, an oscillating lay, a shuttle box on said lay, a friction device for

retarding the shuttle as it enters the shuttle box, a light spring fixed to the lay and engaging said friction device, an arm pivoted to the loom frame and having one end arranged to engage said lay as it moves toward and away from its rearmost position, and spring means arranged to urge said arm into contact with said binder to apply maximum pressure thereto when the lay approaches the rearmost limit of its movement.

2. In a loom, a loom frame, an oscillating lay, a shuttle box on said lay, a shuttle movable into and out of said shuttle box, a binder in said shuttle box for checking the shuttle as it enters the shuttle box, a spring normally engaging the binder and biasing the binder toward checking position, an arm pivoted on the loom frame and arranged to engage said binder as the lay moves toward and away from the rearmost limit of its movement, and spring means engaging said arm and arranged to resist movement of said binder by said shuttle.

3. In a loom, a loom frame, an oscillating lay, a shuttle box on said lay, a shuttle movable into and out of said shuttle box, a binder in said shuttle box for checking the shuttle as it enters the shuttle box, an arm pivoted on the loom frame and arranged to engage the binder as the lay approaches the mid point of its rearward movement to apply increasing pressure on said binder as it approaches the rearward limit of its movement, and means for biasing said arm to apply said pressure to said spring.

4. In a loom, a loom frame, an oscillating lay, a shuttle box on said lay, a shuttle movable into and out of said shuttle box, a binder in said shuttle box for checking the shuttle as it enters the shuttle box, a protecting mechanism arranged to be moved out of protecting position upon engagement of said binder with said incoming shuttle, an arm pivoted to the loom frame and having a portion arranged to engage said binder and to remain in engagement therewith as the lay moves rearwardly from substantially the point of its movement and returns to said point on its forward movement at which the protector mechanism moves out of protecting position, and means engaging said arm and yieldingly resisting rearward movement of said binder to apply substantial checking pressure to the incoming shuttle.

5. In a loom, a loom frame, an oscillating lay, a shuttle box fixed to the lay, a binder supported in said shuttle box for checking the shuttle as it enters the shuttle box, said binder having a portion normally extending into said shuttle box and arranged to be engaged by said shuttle spring means for biasing said binder to normal position, a pivoted arm mounted on said frame and arranged to be engaged by said binder, means for biasing said arm, and adjustable means for limiting forward movement of said arm under the influence of said arm biasing means.

6. In a loom, a loom frame, an oscillating lay, a shuttle box fixed to the lay, a binder supported in said shuttle box and arranged to engage and check said shuttle as it enters the shuttle box, protector mechanism arranged to be moved out of protecting position upon engagement of said binder with said incoming shuttle, and means on the loom frame constructed and arranged to engage and to apply substantial pressure to the binder during only a portion of the forward movement of the lay to insure that the protector mechanism will be maintained in pro-

tecting position prior to complete boxing of the shuttle.

7. In a loom, a loom frame, an oscillating lay, a shuttle box on said lay, a binder in said shuttle box having a portion projecting therein arranged to engage and check an incoming shuttle, means for biasing said binder into checking position, protector mechanism movable out of protecting position upon movement of said binder by an incoming shuttle, an arm mounted on the loom frame and arranged to engage said protector mechanism, and spring means for applying pressure to said arm to cause substantial pressure to be applied to said protector mechanism

10 as the lay approaches and leaves back center to maintain said protecting mechanism in protecting position until a shuttle enters the shuttle box.

8. In a loom, a loom frame, an oscillating lay, a shuttle box fixed to the lay, a binder in said shuttle box having a portion arranged to engage and check an incoming shuttle, means for biasing said binder into checking position, protector mechanism movable out of protecting position

15 upon movement of said binder by an incoming shuttle, a finger on said protector mechanism engaging said binder, an arm pivotally mounted on said loom frame and having portion arranged to be engaged by said finger as the lay oscillates toward and away from its rearward limit of movement, a spring biasing said arm for pivotal movement toward said lay, and adjustable means for limiting movement of said arm toward said lay to determine the point in the rearward movement of the lay at which said finger will engage said arm.

9. In a loom, a loom frame, an oscillating lay, a shuttle box fixed to the lay, a binder in said shuttle box having a portion arranged to engage and check an incoming shuttle, means for biasing said binder into checking position, protector mechanism movable out of protecting position upon movement of said binder by an incoming shuttle, a finger on said protector mechanism

25 engaging said binder, an arm pivotally mounted on the lay and having a portion arranged to be engaged by said finger as the lay oscillates toward and away from its rearward limit of movement, an adjustable spring for biasing said arm toward said lay, and an adjustable stop arranged to limit the forward movement of said arm to cause said finger to engage said arm as the lay approaches the mid point of its rearward movement.
